(57) **CLAIM**

The ornamental design for a gasket scraper, as shown and described.

DESCRIPTION

FIG. 1 is a perspective view of a gasket scraper in accordance with the present invention;

FIG. 2 is a rear elevational view of the gasket scraper;

FIG. 3 is a first side elevational view of the gasket scraper; a second side elevational view being a mirror image of the first side elevational view;

FIG. 4 is a top plan view of the gasket scraper;

FIG. 5 is a bottom plan view of the gasket scraper; and,

FIG. 6 is a front elevational view of the gasket scraper.
